UNITED STATES PATENT OFFICE.

GEORGE E. PARKER AND WILLIAM W. DICKSON, OF AMSTERDAM, NEW YORK.

MATTRESS AND BEDCLOTHES HOLDER.

No. 873,777.

Specification of Letters Patent.

Patented Dec. 17, 1907.

Application filed October 20, 1906. Serial No. 339,788.

To all whom it may concern:

Be it known that we, GEORGE E. PARKER and WILLIAM W. DICKSON, citizens of the United States, residing at Amsterdam, county of Montgomery, and State of New York, have invented certain new and useful Improvements in Mattress and Bedclothes Holders, of which the following is a specification.

10 The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a top plan view 20 of the improved holder, showing the hinged clamping section swung down from the stationary section in which position the clamp is open. Fig. 2 is a side elevation of the holder with the clamp open as shown in Fig.

25 1. Fig. 3 is a view similar to that shown in Fig. 2, except that the clamp is shown closed. Fig. 4 is a view in side elevation of a bedstead, supporting a spring-mattress, a sectional hair mattress and a sheet, the sheet 30 and mattress-sections being held in fixed relation to each other and to the bedstead by our improved holder.

The invention consists of a holding device having clamping members adapted to receive the lower end of a sheet or blanket, and at the same time form a stop against which the lower end of the mattress abuts, and means for holding the device in a stationary position relatively to the bedstead, as will be 40 hereinafter more fully described and pointed out in the claims.

The object of the invention is to prevent the lower section of a sectional mattress from slipping toward the foot of the bed 45 away from the other section, and at the same time prevent the sheet and other bed-clothes from being pulled up away from the foot of the bed.

The holding device is preferably made of 50 wire, as shown in the drawings, although we do not wish to be limited to any particular kind of material or form.

The numeral, 1, represents the body part 55 of the holder, provided with the upright member, 2, which has a double function, serving as a stop or abutment for supporting

the lower end of the lower section of a sectional mattress, and also serves as a clamp-section, coöoperating with the supplementing clamp-section, 3, hinged at, 4, upon the body, 60 1, the hinges, 4, being composed of interlocking eyes formed in the body part and in the hinged sections, 3, as shown in the drawings.

The upper or outer portion of the hinged clamping section is bent over in the form of a 65 hook, as shown more clearly in Figs. 2 and 3 of the drawings at 5.

The hinged clamping-section is shown in Figs. 1 and 2 swung outwardly to an inclined position adapted to permit the end of a sheet 70 or blanket to be inserted between the swinging end of the clamping-section and the hooked end of the upright body member.

To clamp the inserted object between the two clamping-sections, the clamping-section, 75 3, is swung up to the other clamping-section and pressed downwardly until it passes the lower end of the hook-part, 5, so as to clamp the interposed object between the ends of the two sections, as seen in Fig. 5.

In order to swing the section, 3, past the hook, 5, the outer portion of the section, 3, is pushed downwardly below the lower end of hook, 5, the coil-springs, 6, permitting of such depression.

When the clamp is in use any strain upon the inserted fabric, 8, which represents a sheet or blanket used in a bed tends to draw the clamping-sections together so as to increase the clamping effect. The sheet is 90 held between the elongated portions of the clamping-sections marked respectively, 9 and 10, in Fig. 1.

The body-portion of the holder is provided with the arms, 11 and 12, terminating in 95 eyes, 13, adapted to receive one end of a cord or chain, 14, the other end of the cord being provided with a hook 15. The cord may be bifurcated at one end, one of the bifurcations being fastened in one eye, and the other bifurcation in the other eye, as shown in Fig. 1.

In Fig. 4 we have shown our improved holder applied to a bed. The bedstead, 20, which may be of any known form is shown 105 supporting a mattress, 21, which may be an ordinary spring-mattress, or any other form of mattress, being supported in any known manner. Hair mattresses adapted to be placed upon a spring-mattress are usually 110 made in two sections for convenience in manipulation and to permit of one section be-

ing manipulated independently of the other section. 22 represents one section of a sectional mattress, and, 23, represents the other section, both sections being superposed upon 5 the spring-mattress.

Before the mattress-sections are placed upon the spring-mattress our improved device is placed in position, as shown in Fig 4, the body-part resting upon the lower end of 10 the mattress, and being connected by the cord, 14, and hook, 15, with the opposite end of the spring-mattress, as shown, which prevents the holding device from slipping downward toward the foot of the bed. The mattress-sections are then placed upon the spring-mattress, the section, 23, at the foot 15 of the bed resting upon the arms, 11 and 12, and abutting against the vertical portions of the upright member 2. The weight of the 20 mattress-section bearing upon the arms, 11 and 12, serves to maintain the upright member in a vertical position, and the holder bearing against the lower end wall of the lower section, 23, prevents it from slipping 25 toward the foot of the bed and away from the other section, 22, it being apparent from Fig. 4 that without the improved holding device, the section, 23, would be free to slip toward the foot of the bed and leave an 30 opening between the two sections equal to the space between the solid line which divides the two sections and the dotted line 25. The upright-member, 2, also forms a clamping section which coöperates with the hinged 35 clamping section, 3, to hold the lower end of the sheet, 30, in place and prevent its slipping upward toward the head of the bed.

When desired, the lower ends of the blanket or blankets can also be included 40 with the sheet between the clamping sections, but ordinarily it is only necessary to secure the sheet as the bed coverings above the upper sheet will not be pulled up from the foot of the bed unless the sheet is free to 45 move with them.

We are thus able to provide a holding device for beds which will not only prevent the sections of a sectional mattress from separating but will also prevent the bed cover-

ings from being displaced at the foot of the 50 bed. Another advantage of the device is that it is wholly concealed from view and does not in the least interfere with tucking the lower ends of the bed coverings down between the lower end of the mattress and 55 the bedstead in the usual manner.

It is obvious that the length of the cord 14, can be varied so as to accommodate the position of the mattress-resisting abutment to mattresses of different sizes, or so as to 60 retain the mattress at any given desired distance from the foot of the bed.

By the use of a spring-actuated clamping mechanism, the device is easily and quickly operated to secure the bed-clothes in the desired position.

What we claim as new and desire to secure by Letters Patent is

1. A mattress-and-bed-clothes holder comprising a horizontal member adapted to bear against the underside of a mattress-section; an upright member integral with the horizontal member adapted to bear against the lower end of such mattress-section; a spring-actuated clamping section coöoperative with 75 the upright member in forming a clamp; and means for holding the horizontal member from slipping toward the lower end of the bed.

2. A mattress-and-bed-clothes holder comprising a single piece of wire bent to form a horizontal member and an upright member with pivot-eyes at the junction of such members; a second piece of wire bent to form pivot-ends inserted in the pivot-eyes; a pair 85 of coil-springs and a clamping bar coöoperative with the upright member to form a clamp; and means for securing such device from slipping toward the lower end of the bed.

In testimony whereof, we have hereunto set our hands this 18 day of October, 1906.

GEORGE E. PARKER.
WILLIAM W. DICKSON.
